CLAIM

We claim the ornamental design for a pick-up broom attachment with internal water tank, as shown and described.

DESCRIPTION

FIG. 1 is a front perspective view of a pick-up broom attachment with internal water tank according to an embodiment.

FIG. 2 is a front elevational view of the pick-up broom attachment with internal water tank depicted in FIG. 1.

FIG. 3 is a rear elevational view of the pick-up broom attachment with internal water tank depicted in FIG. 1.

FIG. 4 is a right side elevational view of the pick-up broom attachment with internal water tank depicted in FIG. 1.

FIG. 5 is a left side elevational view of the pick-up broom attachment with internal water tank depicted in FIG. 1.

FIG. 6 is a top plan view of the pick-up broom attachment with internal water tank depicted in FIG. 1.

FIG. 7 is a bottom plan view of the pick-up broom attachment with internal water tank depicted in FIG. 1; and,

FIG. 8 is a rear perspective view of the pick-up broom attachment with internal water tank depicted in FIG. 1.

The broken lines in the drawings illustrate portions of the pick-up broom attachment with internal water tank that form no part of the claimed design.
